DESIGN FOR A SHADOW BOX OR SIMILAR ARTICLE

Dixey Barry Carr, New York, N. Y.

Application October 8, 1942, Serial No. 108,466

Term of patent 3½ years

To all whom it may concern:

Be it known that I, Dixey Barry Carr, a citizen of the United States of America, residing in New York city, county of New York, and State of New York, have invented a new, original, and ornamental Design for a Shadow Box or Similar Article, of which the following is a specification, reference being had to the accompanying drawing, forming part thereof, wherein,

I claim:

The ornamental design for a shadow box or similar article, substantially as shown.

DIXEY BARRY CARR.
